(57) **CLAIM**

The ornamental design for a shoe, as shown and described.

DESCRIPTION

6. Shoe

The file of this patent contains at least one color drawing or color photograph. Copies of this patent with color drawing(s)/photograph(s) will be provided by the Office upon request and payment of the necessary fee.

Fig. 6.1 is a perspective view of the shoe according to the present invention;

Fig. 6.2 is a left side view of the shoe of Figure 6.1;

Fig. 6.3 is a right side view of the shoe of Figure 6.1;

Fig. 6.4 is a front view of the shoe of Figure 6.1;

Fig. 6.5 is a back view of the shoe of Figure 6.1;

Fig. 6.6 a top view of the shoe of Figure 6.1; and

Fig. 6.7 is a bottom view of the shoe of Figure 6.1.
